(74) Attorney, Agent, or Firm — Thomas | Horstemeyer, LLP

(57) **CLAIM**

The ornamental design for a package for food, as shown and described.

DESCRIPTION

FIG. 1 is a perspective view showing our new package for food;

FIG. 2 is a front side view thereof;

FIG. 3 is a right view thereof;

FIG. 4 is a left view thereof;

FIG. 5 is a back view thereof;

FIG. 6 is a top side view thereof; and,

FIG. 7 is a bottom side view thereof.

The broken lines show portions of the article that form no part of the claimed design.
